UNITED STATES PATENT OFFICE.

CHARLES M. PROBASCO, OF JAMESTOWN, NEW YORK, ASSIGNOR TO ART METAL CONSTRUCTION COMPANY, OF JAMESTOWN, NEW YORK, A CORPORATION OF NEW YORK.

FILING SYSTEM.

1,054,239.

Specification of Letters Patent. Patented Feb. 25, 1913.

Application filed July 1, 1912. Serial No. 706,948.

To all whom it may concern:

Be it known that I, CHARLES M. PROBASCO, a citizen of the United States, residing at Jamestown, in the county of Chautauqua 5 and State of New York, have invented certain new and useful Improvements in Filing Systems, of which the following is a specification.

This invention relates primarily to what 10 are known as vertical files for the reception of correspondence, bills and other loose papers to which reference must be had from time to time, and it is the object of this invention to provide a means for carrying out 15 the classification and filing of such papers whereby the location of any paper in its particular class or folder may be quickly determined and the paper found with little or no delay. These and other objects of my 20 invention will be fully illustrated in the drawings, described in the specification and pointed out in the claims at the end thereof.

In the accompanying drawings, Figure 1 illustrates a series of filing guides such as are 25 generally used in a vertical filing drawer, arranged according to my invention. Fig. 2 is a detail view of one of the miscellaneous folders used in connection with my filing system. Fig. 3 is a detail view of one of 30 the individual folders used in connection with my filing system.

In my improved filing system I provide essentially three different elements: first, the card which indicates the alphabetical classification, a sample of which card is shown at 35 the front in Fig. 1, indicated by the reference numeral 1. This card has on the top thereof a tab 2 of any suitable design, on which is marked the limits of the alphabetical classification indicated by that particular card. The tabs on the indexing cards in Fig. 1 consist of metal binders fastened to the card, which binders inclose a 40 printed indexing tab or label. This label is printed with the letters that indicate the beginning and the end of the classification for which the particular card in question stands as an index. These letters "Sea— 45 Sem" are separated from each other by a distinct space, and between them and preferably slightly out of line therewith is placed the number of the particular sub-classification indicated by the card, which in the first 50 card shown in Fig. 1 is No. 100 and in the second card shown in Fig. 1 is 101. On

this card may be written the names of the correspondents whose correspondence is classified thereunder, and the card may be specially ruled for this purpose if desired. Next after this card is placed the miscellaneous folder 3, a sample of which is shown in Fig. 2. This folder has a tab formed integral with the rear side thereof, which tab is sufficiently wide to contain thereon the same index markings that are used on the 55 tab of the index card shown in Fig. 1. On the front of these folders can be written in column the names and addresses of the correspondents whose correspondence is contained within the folder. Following the 60 miscellaneous folders are the individual folders 4, a sample of which is shown in Fig. 3. These folders have on the rear side thereof two tabs, one at the left side of the folder and the other at the right. The 65 name of the correspondent to whom the folder applies is preferably placed upon the tab at the left and his address is placed upon the tab at the right. On the one tab or the other the number that is placed upon the 70 tab of the indexing card is also placed. As many of these individual folders may be used under each card as there are correspondents whose names can be placed under the alphabetical subdivision in question. As 75 shown in Fig. 1 the space between the tabs on the individual folders is substantially 80 three times the width of the tabs on the index card and the tabs on the miscellaneous folders. This permits the tabs on the miscellaneous folders and the index cards to be 85 arranged in three distinct lines and I prefer to arrange these lines with all the tabs of the miscellaneous folders in one line preferably the one to the left and the tabs of index 90 cards in two lines, the one in the middle and the one to the right in the middle space in Fig. 1 with the tabs of the index cards arranged alternately first in the one row and then in the other.

My improved file will contain first the indexing card whose tab occurs at the upper edge of the card and substantially at or near the middle of the card. On this card may or may not be placed the names of the correspondents, as may be desired. Following this card is the miscellaneous folder whose tab occurs at the left of the tab on the indexing card, although if desired it may be placed directly in line therewith. Follow- 105 110

ing the miscellaneous folder come one or more of the individual folders, each of said folders having two tabs, one on each side thereof, the tabs occurring on one side in one line on one side of the drawer and the tabs on the other side occurring in a line on the other side of the drawer, with the tab on the indexing cards and the tab on the miscellaneous folder occurring in lines between them and parallel thereto. The next alphabetical subdivision or classification is arranged in a like manner except that the tab on the index card is on the right of the middle space and the foregoing arrangement is then repeated or continued indefinitely up to the capacity of the drawer, as is plainly indicated in Fig. 1, and when the drawer is full the tabs of the indexing cards stand in two uniform lines, one at the middle of the drawer and the other to the right of this middle line, the tabs of the miscellaneous folders standing in the parallel line at the left of the middle of the drawer, and the tabs on the individual folders standing in two continuous lines, one on each side of the drawer, the names of the correspondents being placed on the tabs on one side of the drawer and their addresses being taken on the tabs on the other side of the drawer. The limits of each alphabetical subdivision are repeated on the tabs of both the indexing cards and the miscellaneous folders and the guide number which indicates each alphabetical subdivision is contained upon the tab of the indexing card, the tab of the miscellaneous folder and one of the tabs of each of the individual folders thereunder, the said numbers being preferably placed uniformly on the tabs of the individual folders and being placed between the indexing letters or syllables that indicate the limits of the alphabetical classification upon the tabs of both the indexing cards and the miscellaneous folders.

If desired the indexing cards may be arranged in three different lines with the tabs of each of the miscellaneous folders back of the tab of its index card in each case. Such and other apparent variations are within the spirit of my invention, but I prefer the arrangement set forth at length above and illustrated in Fig. 1.

Having thus described my invention, what I claim as new and patentable is as follows:

1. In a filing system, a series of index cards therein distinguished by having a projecting indexing tab, said tabs having alphabetical designations thereon marking the limits of the alphabetical classification thereunder, said designations being separated by a number corresponding to the alphabetical classification of said card.

2. In a filing system, a series of index

cards, therein distinguished by having projecting label-holders containing labels having alphabetical designations thereon, marking the limits of the alphabetical classification thereunder, said designations being separated by a number corresponding to the alphabetical classification of said card.

3. The combination in a filing system of a series of index cards therein distinguished by having projecting indexing tabs, the said tabs occupying a space in the middle of said cards and of said compartment and being arranged alternately in two parallel lines, combined with a series of folders in groups in said compartment, one group for each card, said folders being provided with indexing tabs on each side of said folders and of said compartment, the tabs of the cards having alphabetical designations thereon marking the limits of the alphabetical classification thereunder, said designations being separated by a number corresponding to the alphabetical classification of said card, the tabs on one side of the folders bearing names of individuals and the tabs on the other side bearing addresses and the number on the tab of the card under which they are classified.

4. The combination in a filing system of a series of index cards therein distinguished by having projecting indexing tabs, the said tabs occupying a space in the middle of said cards and of said compartment and being arranged alternately in two parallel lines, combined with a series of folders in groups in said compartment, one group for each card, said folders being provided with indexing tabs on each side of said folders and of said compartment, the tabs of the cards having alphabetical designations thereon marking the limits of the alphabetical classification thereunder, said designations being separated by a number corresponding to the alphabetical classification of said card, the tabs on one side of the folders bearing names of individuals and the tabs on the other side bearing addresses and the number on the tab of the card under which they are classified, a miscellaneous folder for each group, said miscellaneous folders each having a tab thereon placed so as to occur in series in a single line parallel to the lines of tabs on the index cards and between the lines of tabs on the individual folders.

5. The combination in a filing system of a series of individual folders alphabetically arranged, each of said folders having tabs on the opposite sides thereof with a blank space therebetween, index cards and miscellaneous folders dividing said individual folders into alphabetical groups, said index cards and miscellaneous folders having tabs thereon about one third of the width of the blank space between the tabs on the individual folders, the tabs on the miscel-

lanous folders being arranged in a single line on one side of said middle space and the tabs on the index cards being arranged in two lines occupying the balance of said 5 middle space.

6. The combination in a filing system of a series of individual folders alphabetically arranged, each of said folders having tabs on the opposite sides thereof with a blank 10 space therebetween, index cards and miscellaneous folders dividing said individual folders into alphabetical groups, said index cards and miscellaneous folders having tabs thereon about one third of the width of 15 the blank space between the tabs on the individual folders, the tabs on the miscellaneous folders being arranged in a single line on one side of said middle space and the tabs on the index cards being arranged in 20 two lines occupying the balance of said middle space, the tabs of the cards and miscellaneous folders having alphabetical designations thereon marking the limits of the alphabetical classification thereunder, said 25 designations being separated by a number corresponding to the alphabetical classification of said card, the tabs on one side of the folders bearing names of individuals

and the tabs on the other side bearing addresses and the number on the tab of the 30 card under which they are classified.

7. The combination in a filing system of a series of index cards therein distinguished by having projecting indexing tabs, the said tabs occupying a space in the middle of said 35 cards and of said compartment, and combined with a series of folders in groups in said compartment, one group for each card, said folders being provided with indexing tabs on each side of said folders and of said 40 compartment, the tabs of the cards having alphabetical designations thereon marking the limits of the alphabetical classification thereunder, said designations being separated by a number corresponding to the 45 alphabetical classification of said card, the tabs on one side of the folders bearing names of individuals and the tabs on the other side bearing addresses and the number on the tab of the card under which they are classified. 50

In testimony whereof I affix my signature in presence of two witnesses.
